PLAYGROUND CLIMBER REPRESENTING A CONESTOGA WAGON

Ronald W. Zick, Coldwater, Mich., assignor to
Game Time, Inc.

Filed Feb. 25, 1974, Ser. No. 445,617

Term of patent 14 years

Int. Cl. D21—03

U.S. Cl. D34—5 H

FIG. 1

FIG. 2

FIG. 3

FIG. 4

FIG. 1 is a side, elevational view of the left side of my design, the opposite side being the mirror image thereof;

FIG. 2 is a front elevational view;

FIG. 3 is a rear elevational view; and

FIG. 4 is a top plan view of the design.

I claim:

The ornamental design for a playground climber representing a conestoga wagon, substantially as shown and described.
